UNITED STATES PATENT OFFICE.

LYNDON C. PALMER, OF BUFFALO, NEW YORK, ASSIGNEE TO F. N. BURT COMPANY, LIMITED, OF TORONTO, ONTARIO, CANADA, A CORPORATION OF ONTARIO, CANADA.

METHOD OF MAKING PAPER BOXES.

Application filed June 3, 1919. Serial No. 301,516.

To all whom it may concern:

Be it known that I, LYNDON C. PALMER, a citizen of the United States, residing at Buffalo, in the county of Erie and State of New York, have invented certain new and useful Improvements in Methods of Making Paper Boxes, of which the following is a full, clear, and exact description, such as will enable others skilled in the art to which it appertains to make and use the same.

This invention relates to boxes and methods of making boxes, and with respect to its more specific features, to methods of making paper boxes and parts thereof.

One of the objects of the invention is the provision of a practical method for expeditiously making crimped edge boxes and parts thereof.

Another object of the invention is the provision of an efficient method for the manufacture of the bodies of boxes, especially bodies involving crimped edges for securing the heads or bottoms in place.

Another object of the invention is the provision of a practical method for making crimps in box parts of the character referred to.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification, wherein similar reference characters refer to similar parts throughout the several views—

Figures 1 and 2 are views of strips of material which may be employed in practicing the method;

Fig. 3 is a sectional view of a coiled or wound strip made of the material shown in Fig. 2;

Fig. 4 is a sectional view of the coiled or wound strip of Fig. 3 associated with a coiled or wound strip made of the material illustrated in Fig. 1, and showing a succeeding step of the method;

Fig. 5 is a plan view of the associated coiled strips illustrated in Fig. 4;

Fig. 6 is a sectional view of Fig. 4, illus-

trating a head in position to be secured in place;

Fig. 7 is a view similar to Fig. 6, showing the head held in place by the crimped edge of the outer wound strip; and

Fig. 8 is a sectional view through one embodiment of a completed box.

Referring now more specifically to the drawings, the numeral 1 (Fig. 2) indicates a strip of material which is to be wound or coiled into a ring, as, for instance, the ring shown in Fig. 3, the opposite ends of the strip being circumferentially overlapped, these ends appearing in Fig. 3 at 2 and 3. The numeral 4 (Fig. 1) indicates a strip of material which is to be wound into a ring and its ends overlapped, as shown, for instance, in Fig. 4, where the overlapping ends are indicated by the numerals 5 and 6. The two strips of material are of different widths, the strip 1 being designed to form the inner body portion, or ring, of the box part to be made and the strip 4 being designed to form the outer body portion, or ring, of such part. In practice, the narrower strip 1 is first coated on the outside with adhesive material and wound into a ring with overlapping ends, one or more plies being formed, the adhesive serving to secure the plies together. Then the strip 4, previously coated on the inside with adhesive, as glue, is wound upon the ring 1, one or more plies being formed, and the plies being secured together by the adhesive employed.

By making the width of the strip 1 equal to the depth of the flange, or body, of the box part on the inside, and by making the strip 4 of greater width, the two strips may be associated and wound one upon the other into rings as illustrated in Fig. 4, in which one edge of each ring, as for instance the edges 7 and 8, will be flush with that of the other, in consequence of which the opposite edge 9 of the inner ring will intercept the width of the outer ring and form a shoulder intermediate the width of the outer ring, whereby a portion 10, of the wall of the outer ring will project above such shoulder. There will thus be formed a box body comprising two rings, one surrounding the other and one adhering to the other, and in

each ring the opposite ends of the composing strip will be overlapped so as to avoid butt joints. Furthermore, the thickness of

the rings may be made as desired by continuing the winding more or less so as to make multiple-ply rings, the process thus offering a means for making the box walls 5 thicker or thinner, as desired, by increasing or decreasing the number of plies. There is also afforded opportunity for using thick or thin material as may be desired, the use of thick material requiring a less number of 10 plies than the use of thin material, and the use of thin material enabling a strong box part to be made which otherwise, when in single ply, would have no substantial resistance to crushing and would have to be 15 braced in some manner. Having formed and associated the two rings as illustrated in Fig. 4, a head 11 is placed within the projecting edge of the outer ring so as to rest upon the shoulder formed by the upper edge 20 of the inner ring, as shown in Fig. 6, and thereupon the projecting edge portion 10 of the outer ring is curled or crimped inwardly onto said head, as illustrated at 12, so as to retain the head in position. It is to be understood that box parts made in accordance with the method may be utilized either as the bases or covers of boxes, and in 25 Fig. 8 is illustrated both a base and a cover associated in operative relation.

30 It is to be observed that by sizing the strip 4, as by gluing it on one face so as to provide a glued inner face of that portion 10 of the outer ring which projects above the proximate edge, or shoulder 9, such glued projecting portion of this ring becomes so modified as to be readily adapted for crimping and maintaining crimped condition. The crimping may be effected between dies, one 35 of which will support the box part at one side and the other of which will crimp the projecting edge 10 of the outer ring down onto the head, as illustrated in Fig. 7. The glue or sizing at this portion of the outer ring facilitates the crimping operation as it 40 seems to soften the material at this point and enables it to take the crimp without cracking and provide a smooth bead around the edge. As will be noted, in the present embodiment, the sizing material covers the 45 entire inner face of the strip 4 so as to not only modify the portion to be crimped, but as well to secure the several plies together in ring form, and to the inner ring. In practicing the method, the sizing, as glue, is applied to the strips 1 and 4 before the rings 50 are formed so as to cause the inner and outer rings to adhere to each other. When the crimping is a separate operation, as it may be, the moist sizing may be allowed to dry 55 before the crimping operation is effected. Thereupon, having set the head in place, as for instance the head 11, illustrated in Fig. 6, the crimping is effected through the instrumentality of a heated die which presses 60 against the projecting edge of the outer ring

and not only crimps the same but softens the sizing or glue so as to enable smooth crimping to be effected, whereupon subsequent drying or cooling and setting of the glue tends to firmly retain the turned edge in 70 crimped condition.

It is to be understood that any suitable materials may be employed which are adapted for the purpose. In the present embodiment the inner narrow strip 1 may be of a 75 relatively cheap short fibre paper, as "card middle strip," but preferably will have one finished face which will become the inner face of the ring and form a finished inner face of the box part. The outer ring 4 should preferably be made of a tough fibrous grade of paper, such as craft paper, which has a long fibre, and which is not apt to crack under the strains of crimping. The outer face of the outer ring formed from the 80 strip 4 may be covered with a thin fancy paper to give a desired exterior finish to the box. Various styles of paper may be applied to the outer face to accord with the 85 finish desired. In the present embodiment the box is circular in plan and the rings referred to are consequently circular to comport therewith. It is to be understood, however, that boxes of other shapes may be 90 made by the process. In making the rings it is preferred to employ strips 1 and 4 and to associate them in such manner, in ring form. It is preferred that the grain of one strip run crosswise to that of the other in 95 the assembled rings, whereby a stiffer and more durable box part is formed than would be the case were the grains of both materials parallel. Accordingly, a strip 1 may be 100 formed or selected in which the grain runs longitudinally of the strip, and a strip 4 made or chosen in which the grain runs crosswise thereof, with the result that, in the assembled ring structure, the predetermined shape will be maintained. The sizing 105 employed for the outer strip is preferably animal glue, and the strip is coated to its edge with this glue, so that this glue lies between the plies of the ring made of the strip 4, especially between the plies of the portion 10 which is to be crimped. After the crimping 110 this glue hardens or sets and tends to preserve the crimp and prevent the laminations from unrolling at the crimped edge.

In Fig. 8 a section of a completed box is illustrated, in which the base, or bottom, 13 and the cover, or top, 14 are each formed in accordance with the process above explained. In lieu of a single head 11, the cover is provided with an additional domed head 15, which lies at its margin on the head 11 and is retained by the crimped part 12. In this particular embodiment the box has an inner neck 16, secured to the base and projecting across the plane of meeting 17 of the flanges 125 of the base and cover. The numeral 18 indi- 130

cates a puncturable head which seals the material in the box.

In view of the above are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

15 It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:—

25 1. A method of the character described including coiling a sized strip into a multiple-ply ring while the sizing is moist so as to cause the plies to adhere, allowing the size to dry, softening a multiple-ply sized edge of the ring, and crimping said edge.

35 2. The method of making a box which includes coiling a paper strip of predetermined width into a ring, coiling on said ring a second paper strip into a second multiple-ply ring with one multiple-ply edge thereof projecting above the proximate edge of the first mentioned ring, the portion of the strip which forms the projecting portion of said second ring having a coat of moist sizing during coiling thereof.

45 3. The method of making a box which includes coiling a paper strip of predetermined width into a ring, coiling on said ring a second paper strip into a second multiple-ply ring with one multiple-ply edge thereof projecting above the proximate edge of the first mentioned ring, the portion of the strip which forms the projecting portion of said second ring having a coat of moist sizing during coiling thereof, and crimping said sized projecting portion in the presence of heat after permitting it to dry.

50 4. The method of making a box which in-

cludes coiling a paper strip of predetermined width glued on its outer face into a 55 multiple-ply ring, coiling on said ring a second paper strip in which the grain runs crosswise into a second multiple-ply ring with one multiple-ply edge thereof projecting above the proximate edge of the first 60 mentioned ring, the surface of the strip which forms the projecting portion of said second ring being treated with animal-glue prior to being coiled, placing a head within said projecting portion of said second ring 65 and crimping the projecting portion onto said head in the presence of heat.

5. The method of making a box which includes coiling a short-fibre paper strip in which the grain runs longitudinally into a 70 ring, coiling on said ring a long-fibre second paper strip in which the grain runs crosswise into a second multiple-ply ring with one multiple-ply edge thereof projecting above the proximate edge of the first 75 mentioned ring, the portion of the strip which forms the projecting portion of said second ring having a coat of moist sizing during coiling thereof.

6. A method of the character described 80 including providing a paper ring having dry sizing at one end, softening said sizing and crimping said sized end while the sizing is soft.

7. A method of the character described 85 including providing a multiple-ply paper ring having dry sizing at one end between plies, softening said sizing and crimping said sized end while the sizing is soft.

8. A method of the character described 90 including providing a paper ring having dry sizing at one end, softening said sizing by heat and crimping said sized end while the sizing is soft.

9. A method of the character described 95 including providing a multiple-ply paper ring having dry sizing at one end between plies, softening said sizing by heat and crimping said sized end while the sizing is soft.

100

In testimony whereof I affix my signature, in the presence of two witnesses.
